UNITED STATES PATENT OFFICE.

ALLEN A. TIRRILL, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRICAL REGULATOR.

1,147,573.

Specification of Letters Patent.

Patented July 20, 1915.

Application filed October 5, 1911, Serial No. 653,014. Renewed April 14, 1915. Serial No. 21,448.

To all whom it may concern:

Be it known that I, ALLEN A. TIRRILL, a citizen of the United States, and a resident of Pittsburgh, in the county of Allegheny and State of Pennsylvania, have invented a new and useful Improvement in Electrical Regulators, of which the following is a specification.

My invention relates to electrical regulators, and particularly to regulators of the kind in which the regulation is effected by adjustment of the field excitation of a dynamo-electric machine.

In another application, Serial No. 653,010, filed of even date herewith, I have disclosed and claimed an electrical regulator comprising coöperating contact members, one of which is carried by a lever and actuated by a coil in accordance with variations 20 of the voltage or another electrical condition of a circuit and is, at the same time, vibrated, and the other contact member of which is resiliently mounted and provided with an inclined contact face. In order that 25 the engaging surfaces of the contact members may be of extreme hardness and always clean and free from oxid coatings, they are usually made of iridium, which is very expensive, particularly when obtained in relatively long pieces, such as are necessary 30 for the inclined contact members.

It is the object of the present invention to provide a structure in which the use of a long and expensive inclined contact member 35 is avoided.

The single figure of the accompanying drawing diagrammatically illustrates a system of distribution embodying a regulator constructed in accordance with the present 40 invention.

A system in connection with which the present invention may be conveniently employed comprises an alternating current generator having an armature 1 that is connected to a suitable distributing circuit 2-3-4, and a field magnet winding 5 that is supplied with exciting current from the armature 6 of an exciter. The exciter is provided with a field magnet winding 7 that is preferably shunt-excited, though it may be excited from any other suitable source, and, in series therewith, is a resistor 8, the terminals of which are respectively connected to coöperating contact members 9 and 50 10 of a relay 11, the said contact members

being normally maintained out of engagement by means of a spring 12. The relay 11 is provided with an actuating winding 13 that receives current from the exciter, or from any other suitable source, and the circuit of which is controlled by a pair of coöperating contact members 14 and 15 that constitute parts of the main regulating mechanism.

The contact member 14 is mounted upon the free end of a plate-spring 16, the other end of which is clamped to a stationary post 17, or is otherwise resiliently supported. The contact member 15 is mounted upon one end of an arm 18 having a pivotal support 70 at its other end, and having also an inclined slot or guide 19 for the reception of a pin 20 that is mounted upon one end of a lever 21. The lever 21 is actuated by a winding 22 that receives current that is proportional 75 to the voltage of a circuit 2-3-4, through a transformer 23, but, if desired, it may receive current that is proportional to any other electrical quantity of the said circuit. The winding 22 is provided with a core 25 that is suspended from the lever 21, and the weight of the said core is partially counter-balanced by means of an adjustable counter-weight 26. The movements of the core 25 and the lever 21 and their attached 80 parts are preferably somewhat retarded by means of a dash pot 27. As the voltage of the circuit 2-3-4 varies, the core 25 is moved up and down, and, by reason of the provision of the slot- and pin-connection between the lever 21 and the arm 18, the distance of the contact member 15 from the member 14 is correspondingly varied.

The lever 21 is pivotally supported by the substantially vertical arm of a beamrank 95 lever 29 having a stationary fulcrum at 30 and carrying a magnetizable core 31 at the end of its other arm. The core 31 is surrounded by an actuating coil 32 that receives current from the distributing circuit 2-3-4, or from any other suitable source, and the circuit of which is governed by coöperating contact members 33 and 34 of a relay 35, the movements of the core 31 and associated parts being preferably somewhat retarded by means of a dash pot 36. A spring 37 serves to normally maintain the contact members 14 and 15 in engagement. The relay 35 is provided with an actuating winding 38 that is connected in parallel 110

with the winding 13 of the relay 11 in order that its circuit may be controlled in a similar manner.

The manner in which the regulator operates will be best understood from a detailed consideration thereof. If the voltage of the circuit 2-3-4 becomes reduced, as, for instance, because of an increase of load, the winding 22 becomes somewhat less strongly energized and the core 25 is correspondingly lowered, with the result that the contact member 15 is moved slightly closer to the member 14. When the circuit of the winding 32 is interrupted, the spring 37 causes the contact member 15 to engage the member 14, and the relay-actuating windings 13 and 38 are thereupon energized to cause the contact members 9 and 33 to engage the corresponding members 10 and 34. When the members 9 and 10 engage, a shunt circuit to the resistor 8 is established, followed by an increase in the field excitation and voltage of the exciter and by corresponding increases of the field excitation and voltage of the main generator. When the voltage of the generator is increased, the winding 22 becomes somewhat more strongly energized, with the result that the contact member 15 is moved slightly away from the member 14. When the members 33 and 34 engage, the circuit of the winding 32 is established and the contact member 15 is thereupon moved out of engagement with the member 14, in opposition to the tension of the spring 37. Upon separation of the contact members 14 and 15, the circuit of the actuating windings of the relays is interrupted, followed by interruptions of the shunt-circuit to the resistor 8 and the circuit of the winding 32. The field excitations and voltages of the exciter and main generator then increase somewhat and the spring 37 again causes the contact member 15 to engage the member 14. The regulator continues to operate in this manner, the contact member 15 being rapidly moved into and out of engagement with the member 14, and the periods of engagement and disengagement of the said members depending upon the initial position of the member 15, as determined by the voltage of the circuit 2-3-4 through the winding 22. The regulator operates to maintain the voltage of the circuit 2-3-4 at a substantially uniform value, or at any desired value, depending upon a predetermined electrical condition of the circuit.

It will be understood that, by means of simple changes which may be made by anyone skilled in the art, the regulator may be

adapted for other purposes than voltage regulation, and may be caused to regulate in accordance with variations of any desired electrical condition of a circuit. It may also be employed for the regulation of direct current machines, as well as for the regulation of alternators.

I claim as my invention:

1. An electrical regulator comprising co-operating contact members, an arm carrying one of said members and having an inclined guide, an actuating lever for said arm having a member operating in said guide, a second lever providing a fulcrum for the aforesaid lever, and means for actuating the said levers. 75

2. An electrical regulator comprising co-operating contact members, a movable support for one of said members, an actuating lever for the support having an inclined slot-and-pin connection therewith, a second lever providing a fulcrum for the aforesaid lever, and actuating means for the said levers. 80

3. An electrical regulator comprising co-operating contact members, a movable support for one of said members, a substantially horizontal actuating lever for the support having an inclined slot-and-pin connection therewith, a second lever having a substantially vertical arm providing a fulcrum for the aforesaid lever, and actuating means for the said levers. 85 90

4. An electrical regulator comprising co-operating contact members, a movable support for one of said members, an actuating lever for the support, a second lever providing a fulcrum for the aforesaid lever, and actuating means for the levers. 95

5. An electrical regulator comprising co-operating contact members, a movable support for one of said members, an actuating lever for the support having a can connection therewith, a second lever providing a fulcrum for the aforesaid lever, and actuating means for the said levers. 100 105

6. An electrical regulator comprising co-operating contact members, an actuating lever for one of said members having a can connection therewith, a second lever providing a fulcrum for the aforesaid lever, and actuating means for the said levers. 110

In testimony whereof, I have hereunto subscribed my name this 3rd day of October, 1911.

ALLEN A. TIRRILL.
